UNITED STATES PATENT OFFICE

2,527,459

FASTENER

Charles H. Shook, Dayton, Ohio

Application September 18, 1947, Serial No. 774,753

6 Claims. (Cl. 189—35)

1

This invention relates to a fastening device for holding a plurality of structural members together.

Recently, there has been developed a form that can be assembled in regular units for the purpose of providing wall forms into which concrete footers and vertical walls may be poured. The various sections of the forms are constructed from metal channels, the assembly of which has required the placement of holes in the various form parts to receive bolts for securing the assembly together.

It is therefore an object of this invention to provide a fastening device for holding a plurality of structural members together which may be readily removed to provide for quick assembly and disassembly of the structural members and does not require the placement of any holes in the members.

Still another object of the invention is to provide a fastening device for the purpose of the foregoing object that is a formed wire member.

Still another object of the invention is to provide a fastening device of the type and for the purpose of the foregoing objects that is formed in such a manner as to prevent relative movement between the structural members when the fastening device is assembled upon the members.

Still another object of the invention is to provide a fastening device of the type and for the purpose of the foregoing objects that is particularly adapted to removably secure horizontally positioned channel members against vertically positioned channel members so that the horizontally positioned channel members can all be secured to the vertically positioned channel members to provide a vertical wall form without requiring the use of any tying members between the horizontally disposed channel members.

Further objects and advantages will become apparent from the drawings and the following description:

In the drawings:

Figure 1 is a perspective cross-sectional view of a wall section illustrating the use of the fastening device of this invention to hold the structural members together.

Figure 2 is a vertical cross-sectional view taken substantially along line 2—2 of Figure 1.

Figure 3 is a top plan view of the structural members illustrating the fastening device for holding them together.

Figure 4 is a front elevational view illustrating the fastening device in position on the vertical structural members.

2

There has recently been developed a form which consists of a plurality of like wall channel sections that are adapted to be positioned one upon the other and braced by suitable vertically positioned members to thereby provide wall forms between which concrete can be poured. The vertical members, or studs, are adapted to be secured to the horizontal sections that compose the wall form to prevent the horizontal members from falling inwardly. The fastening means or devices have not been wholly satisfactory for they require the placement of holes in the various wall sections through which bolts may be placed to secure the assembled members in their proper position.

In this invention the prior use of bolts and holes in the structural members forming the wall forms and studs are eliminated, and a simple formed wire is provided to secure the horizontally disposed sections of the wall form to the vertical studs, the wire fastening devices being sufficiently resilient to allow for their easy insertion and removal for assembly and disassembly of the various wall form members.

The wall forms may consist of a pair of channels 10 and 10a adapted to rest upon the ground that are of sufficient height to form a suitable footer. These channels 10 and 10a are secured in parallel relationship by means of spikes or rods 11.

A suitable footer may be poured between the channel sections 10 and 10a. The footer may then provide a part of the support upon which the vertical wall forms rest.

The vertical wall forms consist of a plurality of channels 12 and 12a that are assembled one upon the other to any desired height. The channel sections 12, however, would fall inwardly relative to each other if they were not braced by suitable vertical studs, such as the studs 13 and 13a. Each of the wall channels 12 is provided with flanges 15 and 16 that extend along the lower and upper edge, respectively, of the channels. While there is disclosed the use of continuous flanges 15 and 16 along the wall sections 12, yet other protrusions can be provided for the purpose of receiving and cooperating with the fastening devices, as will be apparent herein-after.

Each of the vertical studs 13 and 13a consists of a pair of channels 17 and 17a that are adapted to be positioned with the flat faces of the channel in adjacent relationship.

The fastening device for holding the horizontally disposed channel forms 12 to the vertical

studs 13 and 13a consists of a wire form member 20, more particularly shown in Figures 2, 3 and 4.

The fastening device 20 consists of a vertical leg 21 that is adapted to be positioned between the pair of channels 17 and 17a that form the vertical studs 13 or 13a. This vertical leg 21 has at its upper end a horizontal leg 22 and a corresponding horizontal leg 22a at the lower end thereof that passes to the forward or face edge of the channels 17 and 17a. The horizontal legs 22 and 22a are then bent normal to the legs 22 and 22a to form leg portions 23 and 23a that extend in diametrically opposite directions from the vertical leg 21 and normal thereto. The legs 23 and 23a are of just sufficient length to equal the width of the face of the channels 17 and 17a.

The legs 23 and 23a of the fastening device 20 are then bent normal to themselves to form leg portions 24 and 24a so as to lay parallel to each other and parallel to the legs 22 and 22a of the fastening device. The legs 24 and 24a terminate in oppositely disposed hook portions 25 and 25a that are adapted to extend over the flanges 16 and 15 respectively of the wall channels 12.

From the foregoing description it will therefore be seen that the fastening device may be disposed with the hook portion 25 in engagement with the upper flange 16 of the wall channel 12 so that the leg portions 24, 23 and 22 wrap around the vertical channel 17. Correspondingly, the hook portion 25a engages the lower flange 15 of the channel 12 with the leg portions 24a, 23a and 22a wrapped around the channel 17a. The vertical leg portion 21 spaces the two wrap-around portions of the fastening device at substantially the level of the upper and lower flanges.

One of the fastening devices 20 may be used to hold each of the wall channels 12 in position against the vertical studs 13 and 13a. It will be apparent that there will be required no holes or bolts to hold the assembly together.

With the fastening devices 20 in position between the wall channels 12 and the studs 13, the wall channels 12 are prevented from falling away from the studs 13 and the studs 13 are prevented from moving parallel to the wall channels 12. The resilient wire forms which provide the fastening devices of this invention therefore make a rigid assembly of the wall channels 12 to the vertical studs 13.

While the device described and disclosed herein constitutes a preferred form of the invention, yet it may be modified without departing from the spirit of the invention, and all such modifications are intended to be included in the appended claims.

Having thus fully described my invention, what I claim as new and desire to secure by Letters Patent, is:

1. In combination, a structural member comprising a pair of substantially parallel individual members, a second structural member disposed against said first structural member and normal to a parting line between the individual members comprising the first structural member, and a fastening device securing all of said structural members together consisting of; a leg portion disposed between the individual members comprising said first structural member, loop portions extending in the same direction from each of opposite ends of said leg portions but in opposite directions relative to each other and each loop portion extending around one of the individual members comprising said first-mentioned struc-

tural member disposed on opposite sides of said leg portion, said loop portions extending into engagement with said second structural member and having means on the ends thereof securing the same to said second structural member.

2. In combination, a structural member comprising a pair of substantially parallel individual members, a second structural member disposed against said first structural member and normal to a parting line between the individual members comprising the first structural member, and a fastening device securing all of said structural members together consisting of; a leg portion disposed between the individual members comprising said first structural member, loop portions extending in the same direction from each of opposite ends of said leg portions but in opposite directions relative to each other and extending around the respective individual members forming said first-mentioned structural member, said loop portions being disposed in substantially parallel planes and having leg portions extending into engagement with said second structural member securing the same thereto.

3. In combination, a structural member comprising a pair of substantially parallel individual members, a second structural member disposed against said first structural member and normal to a parting line between the individual members comprising the first structural member, and a fastening device securing all of said structural members together consisting of; a leg portion disposed between the individual members comprising said first structural member, loop portions extending in the same direction from each of opposite ends of said leg portions but in opposite directions relative to each other and extending around the respective individual members forming said first mentioned structural member, said loop portions being disposed in substantially parallel planes and having leg portions extending toward said second structural member and arranged in the plane of their respective loop portions substantially parallel to each other, said last-mentioned leg portions having loop portions extending therefrom engaging said second structural member whereby to secure the fastening device thereto and to secure said structural members together.

4. In combination, a structural member comprising a pair of substantially parallel individual members, a second structural member disposed against said first structural member and normal to a parting line between the individual members comprising the first structural member, and a fastening device securing all of said structural members together consisting of; a leg portion disposed between the individual members comprising said first structural member, loop portions extending in the same direction from each of opposite ends of said leg portions but in opposite directions relative to each other and extending around the respective individual members forming said first mentioned structural member, said loop portions being disposed in substantially parallel planes and having leg portions extending toward said second structural member and arranged in the plane of their respective loop portions substantially parallel to each other, said last-mentioned leg portions having loop portions extending therefrom engaging said second structural member whereby to secure the fastening device thereto and secure said structural members together, said last-mentioned loop portions extending in opposite directions from their respec-

tive leg portions and laying in substantially parallel planes substantially normal to the planes of said first mentioned loop portions.

5. A fastening device consisting of, a leg portion, a U-shaped loop portion extending from each end of the leg portion in the same direction therefrom but in opposite directions relative to each other, said loop portions laying in planes at each end of said leg portion substantially parallel to each other and substantially normal to the said leg portion, each of said loop portions having a leg portion laying in the plane of the respective loop portion, said last-mentioned leg portions being disposed in substantially parallel relationship in their respective planes and each terminating in a U-shaped loop portion, said last-mentioned loop portions extending in opposite directions relative to each other from their respective leg portions.

6. A one-piece wire fastening device consisting of, a leg portion, a U-shaped loop portion extending from each end of the leg portion in the same direction therefrom but in opposite di-

rections relative to each other, said loop portions laying in planes at each end of said leg portion substantially parallel to each other and substantially normal to the said leg portion, each of said loop portions having a leg portion laying in the plane of the respective loop portion, said last-mentioned leg portions being disposed in substantially parallel relationship in their respective planes and each terminating in a U-shaped loop portion, said last-mentioned loop portions extending in opposite directions relative to each other from their respective leg portions.
